UNITED STATES PATENT OFFICE.

FREDERICK W. WOOD, OF KANSAS CITY, MISSOURI.

TENSION-GOVERNOR FOR PNEUMATIC APPARATUS.

1,115,999.

Specification of Letters Patent.

Patented Nov. 3, 1914.

Application filed December 31, 1913. Serial No. 309,702.

To all whom it may concern:

Be it known that I, FREDERICK W. Wood, a citizen of the United States, and a resident of Kansas City, in the county of Jackson and State of Missouri, have invented certain new and useful Improvements in Tension-Governors for Pneumatic Apparatus, of which the following is a specification.

This invention relates to tension governors for pneumatic apparatus.

The object of my improvements is to provide a device of the class specified, simple in construction and efficient and prompt in operation.

Before describing the invention in detail I desire to have it understood that the invention is not limited to the particular construction and arrangement of parts which I have illustrated and shall hereinafter describe, and that various changes may be made in the mechanism shown without departing from the spirit or scope of the invention, and that the phraseology which I employ is for the purpose of description and not of limitation.

In the drawings accompanying this specification is illustrated the preferred embodiment of my improvements, wherein—

Figure 1 is a sectional side elevation, partly diagrammatic, of so much of a pneumatic apparatus as is necessary to illustrate said improvements. Fig. 2 is a diagrammatic sectional elevation similar to that of Fig. 1, and showing some of the parts in positions different from those of Fig. 1. Fig. 3 is a diagrammatic view similar to that of Fig. 2, illustrating a further change in position of some of the parts. Figs. 2 and 3 are to a smaller scale than that of Fig. 1.

I have illustrated my improvements as particularly adapted for use in connection with a pneumatic piano player, and as employed therein for accenting any given note by increasing or decreasing the hammer blow by means of the increase or decrease of the tension in the reservoir connected with the operative pneumatics of the aforesaid hammers. While I have not shown said hammers or operative pneumatics, they are well known in the art and the application of this device thereto will be readily understood.

The usual tension chamber 2, is provided with a suction pipe 3, by which the air may be exhausted by some convenient means, such as an air pump of some well known construction. In this connection, it will be observed

that my improved device is particularly applicable to a pneumatic piano in which the air pump is driven by power and in which the whole apparatus is automatic. Pipe 4 at the left hand end of said chamber may connect with the pneumatic action of the piano, as well understood. Said chamber 2 is provided with a plurality of air inlet valves, preferably three in number, 5, 6 and 7. Said valves are of the same general construction and a description of one will suffice for all. Said valve 5 is fixed to one end of stem 8 and which stem passes outwardly through a convenient aperture in wall 9 of chamber 2, and thence through an aperture in bracket 10 fixed to said wall 9. The seat for valve 5 may be dished at 11 and said dished portion may be connected by channels 12, 12 with the outside atmosphere. Said stem 8 may be provided with spring 13 therearound and with nut 14 threaded thereon, for varying the tension of said spring and thereby the power for closing said valve. Spring 15 for the stem of valve 6 is of less strength than that of spring 13, and spring 16 on the stem of valve 7 is of greater strength than spring 13.

For locking valve 6 (the low pressure valve) in its closed position, I provide the following: Diaphragm 17 is mounted in the usual manner over pocket 18 in wall 19 of chamber 2, and said diaphragm may be provided with button 20 having the usual bleed hole therethrough. Said button in its operative movement engages extension 50 of valve 6. Pocket 18 is connected with the outside atmosphere by pipe 21. Means for closing the outer end of said pipe comprises valve 22, fixed to the free wall 23 of pneumatic 24. Said pneumatic 24 is connected by pipe 25 with valve chamber 26. Valve chamber 26 is provided with an opening 27 into chamber 28, connected by channel 29 with chamber 2. Said valve chamber 26 is also connected with the outside atmosphere by opening 30, and the usual valve 31 is provided in said chamber for alternately closing openings 27 and 30. Said valve 31 is actuated to close against opening 30 by means of the usual diaphragm 33 in engagement with the end of stem 34 of said valve. Chamber 32 below said diaphragm 33, is connected with aperture 35 in tracker bar 36 by means of pipe 37.

For locking valve 5 (the medium pressure valve) against opening, I provide dia-

phragm 38 over pocket 39 in wall 19 of chamber 2. Said diaphragm is provided with button 40 for engaging extension 41 of said valve 5. Pocket 39 is connected by pipe 42 with pocket 43. Valve 44 is provided for closing pocket 43 against the atmosphere. For lifting valve 44 by means of its stem 47, I provide diaphragm 45 over pocket 46. Said pocket 46 is connected by pipe 48 with aperture 49 in tracker bar 36.

High pressure valve 7 is unprovided with any means for locking in closed position, for reasons which will appear in the following description of the operation of my improvements.

Assuming that a suitable note sheet is arranged to pass downwardly over tracker bar 36 and that air is being constantly exhausted from chamber 2, the operation of my improved device is as follows: When apertures 35 and 49 are covered by the note sheet as in Fig. 3, low pressure valve 6 will be held in its closed position by atmospheric pressure through pipe 21 against diaphragm 17, urging button 20 against extension 50 of said valve 6. Furthermore, as hereinbefore described, spring 16 of valve 7 is more powerful than spring 13 of valve 5, whereby said valve 7 will be maintained against its seat in wall 9 of chamber 2, and if said chamber 2 is sufficiently exhausted, air will leak thereinto around valve 5 against the pressure of spring 13, whereby the tension of said chamber will be maintained at a uniform amount, gaged by the power of said spring 13. This condition is assumed to be the normal working condition of my device and the tension in chamber 2 may be described as "medium tension." If now it is desired to accent by increasing the blow of any given note or notes, such for instance as indicated by opening 52 in note sheet 51, I provide perforation 53 in said note sheet, located, longitudinally for timing with said opening 52 and transversely to register with tracker bar aperture 49. When said perforation 53 passes over aperture 49, air is admitted into that aperture and through pipe 48 to below diaphragm 45. Said diaphragm is thereupon forced by the air against the end of stem 47 and valve 44 is lifted from its seat, thereby admitting air into chamber 43 and through pipe 42 to the underside of diaphragm 38. Said diaphragm is thereupon forced by air pressure against extension 41 of valve 5, whereby said valve is locked against its seat in wall 9, see Fig. 1. It will thus be seen that low pressure valve 6 and medium pressure valve 5 are locked against opening. Continued suction through pipe 3, will therefore increase the tension in said chamber 2, whereby the note corresponding with perforation 52, drawing its sources of power from said chamber 2, will be struck a heavier blow

than as if either or both valves 5 and 6 were free to open under the tension of chamber 2. To cause this high tension to be uniform in amount, high pressure valve 7 is provided so that upon any tendency to exhaust chamber 2 beyond the resisting tension of spring 16 said valve 7 will be unseated and air will leak into said chamber to an amount in accordance with the power of spring 16. If now it is desired to accent by softening any given note or notes, such for instance as indicated by perforation 54 in the note sheet, Fig. 2, perforation 55 is provided, suitably located transversely of the note sheet to register with aperture 35 in the tracker bar. When said perforation passes over aperture 35 air is admitted to the aperture, and through pipe 37 to chamber 32, whereby diaphragm 33 is forced against the end of stem 34 of valve 85 31, moving that valve to close opening 30 against the atmosphere and uncover opening 27 connected with suction chamber 2. Air is thereby exhausted from chamber 26 and, through pipe 25, pneumatic 24 is caused to collapse, closing valve 22 against the outer end of pipe 21. This permits diaphragm 17 to withdraw from against extension 50 of low pressure valve 6 whereby that valve is permitted to come into active operation. The tension in chamber 2, having previously been held at mid-pressure by spring 13, is now sharply reduced to low pressure, by the opening of valve 6 against low power spring 15, whereby the note corresponding with opening 54 in the note sheet will be struck a soft blow as desired.

It will be obvious that springs 13 and 15 may be of the same power if valves 5 and 6 vary in their effective areas. It will also be obvious to those skilled in the art that if the maximum tension exerted through pipe 3 is automatically maintained at the desired amount to produce the requisite heavy accent, valve 7 may be dispensed with and tension of three degrees produced, through governing means for valves 5 and 6 as described. However, I consider it preferable in practical use to employ valve 7 as well as valves 5 and 6, particularly for conveniences of adjustment and manipulation.

I claim:

1. A tension governor for pneumatic apparatus including in combination a chamber, means for exhausting air therefrom, a plurality of air inlet valves to said chamber, means for closing said valves, and means for locking one or more of said valves in their closed positions.

2. A tension governor for pneumatic apparatus including in combination a chamber, means for exhausting air therefrom, a plurality of air inlet valves to said chamber, means for closing said valves, said closing

means varying in power from one valve to another valve, and means for locking one or more of said valves in their closed positions.

3. A tension governor for pneumatic apparatus including in combination a chamber, means for exhausting air therefrom, a plurality of air inlet valves to said chamber, means for closing said valves, said closing means varying in power from one valve to another valve, means for regulating the power of said closing means for any given valve, and means for locking one or more of said valves in their closed positions.

4. A tension governor for pneumatic apparatus including in combination a chamber, means for exhausting air therefrom, a plurality of air inlet valves to said chamber, means for closing said valves, said closing means varying in power from one valve to another valve, means for locking one or more of said valves in their closed positions, a tracker bar having a plurality of apertures therein, means governed by the uncovering of one of said apertures for actuating said locking means for one valve, and means governed by the uncovering of another of said apertures for actuating the locking means of another of said valves.

5. A tension governor for pneumatic apparatus including in combination a chamber, means for exhausting air therefrom, three air inlet valves to said chamber, independent means for closing each of said valves, means for locking one of said valves, means for locking another of said valves, a tracker bar having a plurality of apertures therein, means governed by the uncovering of one of said tracker bar apertures for actuating the locking means of the first mentioned valve for unlocking that valve, and means governed by the uncovering of another of said apertures for actuating the locking means of the second mentioned valve for locking that valve.

45 6. A tension governor for pneumatic apparatus including in combination a chamber,

means for exhausting air therefrom, three air inlet valves to said chamber, independent means for closing each of said valves, the power of said closing means for one valve 50 being greater than that for one of the other valves and less than that for the third valve, means for locking the low pressure valve, means for locking the medium pressure valve, a tracker bar having a plurality of 55 apertures therein, means governed by the uncovering of one of said tracker bar apertures for actuating the locking means of the low pressure valve for unlocking that valve, and means governed by the uncovering of another 60 of said apertures for actuating the locking means of said medium pressure valve for locking that valve.

7. A tension governor for pneumatic apparatus including in combination a chamber, 65 means for exhausting air therefrom, three air inlet valves to said chamber, independent means for closing each of said valves, the power of said closing means for one valve being greater than that for one of the other 70 valves and less than that for the third valve, means for regulating the power of said closing means for any given valve, means for locking the low pressure valve, means for locking the medium pressure valve, a tracker 75 bar having a plurality of apertures therein, means governed by the uncovering of one of said tracker bar apertures for actuating the locking means of the low pressure valve for unlocking that valve, and means governed 80 by the uncovering of another of said apertures for actuating the locking means of said medium pressure valve for locking that valve.

Signed at Kansas City, in the county of 85 Jackson and State of Missouri, this 16 day of December, 1913, before two subscribing witnesses.

FREDERICK W. WOOD.
